PRIMARY ZONE FOR GAS TURBINE COMBUSTOR

Willard L. Christensen, Newtown, Conn., assignor, by
mesne assignments, to the United States of America as
represented by the Secretary of the Navy

Application October 23, 1956, Serial No. 617,895

2 Claims. (Cl. 60—39.71)

This invention relates to a primary burning zone for a 15
gas turbine combustor.

In gas turbine engines, jet combustion is accomplished
by the continuous burning of fuel in a confined space
to obtain power directly from the hot products of com-
bustion. In such engines a high velocity air stream is
forced by a compressor into the combustion chamber
where fuel is mixed with the compressor air. Combustion
occurs primarily in the flame zone and this provides
the working medium for the turbine.

The optimum performance of a compressor-burner-
turbine type engine is to obtain the highest stable heat
release in the combustion chamber. This high efficiency
should be for a wide range of fuel rates and air flow
conditions. Since there are few variables in a given en-
gine design, a basic method of obtaining increased ef-
ficiency is to pre-treat the fuel to stabilize the flame.
The performance is greatly increased if a catalytic agent
can be employed in the primary zone to provide a stabi-
lized region of burning.

The present invention pre-treats the fuel by a heated
target which utilizes the heat from the burning gases in
the primary zone. The incoming fuel is directed at high
velocity onto the target where it is heated to vaporiza-
tion and combines with hot gases. This mixture is then
united with the primary air from the compressor and
introduced into the combustion chamber. To assist in
complete burning in the unit the target may be coated
with a catalytic agent. Thus, burning efficiency is in-
creased and stabilized enabling a great reduction in length
and weight.

It is an object of this invention to provide a gas tur-
bine combustor wherein the income fuel is pre-treated
by a heated target.

It is a further object of this invention to provide a gas
turbine combustor wherein the injected fuel is vaporized
by heat derived from the primary burning section.

Other objects and many of the attendant advantages
of this invention will be readily appreciated as the same
becomes better understood by reference to the following
detailed description when considered in connection with
the accompanying drawing, the single figure of which
shows a cutaway longitudinal section through a gas tur-
bine combustor embodying the invention.

Referring more particularly to the drawing, the pre-
ferred embodiment of the invention includes a gas turbine
combustor having an outer casing 1. Mounted within
and spaced from the outer casing 1 is an open ended
cylindrical casing 2 having a plurality of openings 3
through which the necessary secondary or cooling air
may enter. Casing 2 is rigidly connected to casing 1 by
a plurality of struts extending between the casings, two
of the struts 38 and 40 being shown and being secured
to the casings by any suitable means such as welding.

A circular baffle 4 is located in the forward end of
the cylindrical casing 2. A fitting 5 on the baffle 4 re-
ceives the fuel line 6 so that fuel may be ejected through
the baffle. Spaced from the rearward side of the baffle 4

2

there is a circular ceramic target 7 having a downstream
face 8 and an upstream face 10. The target 7 is po-
sitioned parallel to but spaced from the baffle 4 so that
fuel ejected from the fitting 5 will impinge on the target.
5 The downstream face 8 of the target is exposed to the
primary combustion zone 9. The hot gases in the com-
bustion zone 9 heat the ceramic target 7 so that the fuel
directed on the target 7 by the fitting 5 is vaporized.
Both the downstream face 8 and the upstream face 10
10 of the target 7 are coated with a catalytic agent. As
a general rule, catalytic agents are not effective on a
surface that is wetted by fuel. However, since the up-
stream face 10 of the target 7 in the preferred embodi-
ment of the invention is at a sufficiently high tempera-
ture, the upstream face 10 will be in a gaseous area and
a catalytic agent would thus be effective.

A fuel mixing chamber 11 is located between the baffle
4 and the target 7. This chamber is partially enclosed
by a tapering circular shield 12. The front end 13 of
20 the shield 12 is parallel to but spaced from the curved
lip portion 14 of the baffle 4 providing an annular open-
ing 15 through which the fuel mixture may pass. The
other end 16 of the shield 12 is concentric to but spaced
from the target 7 to form a ring shaped opening 17
25 through which some of the hot gases from the primary
combustion zone 9 may pass. The baffle 4, the target
7 and the shield 12 are secured together to form one
unit and the unit is mounted in the forward end of the
casing 2. Baffle 4 and shield 12 are rigidly connected
30 by a plurality of strut members 24, 26 and 28 and target
7 is connected to the end 16 of shield 12 by a plurality
of pins 30 (only two shown). The unit assembly of
baffle 4, target 7 and shield 12 is in turn rigidly attached
35 to cylindrical casing 2 by strut members 32, 34 and 36
which extend between casing 2 and shield 12 and which
may be secured thereto by any suitable means such as
welding.

The primary air is introduced through an annular
40 venturi 18 surrounding the fuel chamber. The venturi
18 is formed by a ring shaped member 19 having a
curved side wall 20 concentric with and spaced from
the curved lip portion 14. The side wall 20 extends
45 rearwardly past the end 13 of the section 12. The mem-
ber 19 is mounted on the casing 2 to provide an annular
opening 21. Member 19 is connected to casing 2 in this
preferred embodiment by a plurality of rods 42 (only
50 two shown) which extend between the member 19 and
casing 2 and which are secured thereto by any suitable
means such as by welding (not shown). It will be ap-
preciated, however, that any suitable type of connecting
means other than rods 42 may be used.

In operation of the target 7 is heated to a high tem-
perature by the hot gases in the primary combustion
55 chamber. Fuel is injected into the fuel mixing chamber
11 and is vaporized by the heated target. The vaporized
fuel then mixes with the hot gases entering the fuel mix-
ing chamber through the circular opening 17. As the
primary air passes through the annular venturi 18 sur-
60 rounding the fuel mixing chamber, it draws the fuel-hot
gas mixture out of the chamber and into the high velocity
primary air stream. The turbulence caused by the ex-
pansion at locations 22 thoroughly mixes the combustible
elements so that they may be ignited and burned in
65 the primary chamber.

This type of gas turbine combustor primary zone is
applicable to either a can or an annular type burner
where a series of these chambers would be arranged on
the upstream face.

70 Obviously many modifications and variations of the
present invention are possible in the light of the above
teachings. It is therefore to be understood that within

the scope of the appended claims the invention may be practiced otherwise than as specifically described.

What is claimed is:

1. A primary zone for a gas turbine combustor comprising an outer casing, an inner cylinder mounted in said casing and open at both ends, a fuel supply means mounted in said casing in the center thereof and adjacent one end of said cylinder, an annular venturi surrounding said fuel supply means through which primary air flows, an annular shield mounted in said cylinder spaced from said venturi and forming a fuel and air mixing chamber, a ceramic target mounted in said mixing chamber and being of a lesser diameter than the inner diameter of the chamber whereby hot gases from the rest of the cylinder which forms a primary combustion zone will pass between said target and said shield and vaporize

10
5
15

the incoming fuel and the primary air passing through the venturi will draw the mixture thus formed into the primary combustion zone.

2. A primary zone for a gas turbine combustor as in claim 1 wherein the ceramic target is coated with a catalytic agent.
